UNITED STATES PATENT OFFICE.

SAMUEL R. LEWIS, OF CHICAGO, ILLINOIS.

HEATING AND VENTILATING DEVICE.

Application filed August 20, 1925. Serial No. 51,432.

This invention relates to an indirect heating and ventilating device for buildings, and has for its object the provision of a device adapted to be supported on the floor of a building adjacent a window and against the wall, and in which the heated air is driven by a blower to conduits through the device for directing air upwardly and outwardly into a room at an acute angle to the floor, and in which a restricted opening is provided to act as a nozzle for forcing the air forwardly and upwardly in order to promote rapid circulation.

A further object of the invention is the provision of a device in the form of a grille for supplying air to a room, and in which the supply pipe or heating medium is supported on the device while the return pipe is located within the same in order that not only certain pipes will be properly concealed in the room but that a great deal of the heat which is ordinarily lost will be employed for increasing the temperature of the incoming air.

A still further object of the invention is the provision of a grille for supplying air to the room and which will act as a nozzle for forcing the air diagonally across the room and also provide a support for a radiator through which the air is directed before being admitted to said room.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient feature of the invention as expressed in the appended claims.

In the drawings:

Figure 1 is a vertical section of the grille in the approved form of my invention,

Figure 2 is a vertical section of the grille shown in Figure 1, and in which the supply and return pipes of a heating system are carried by the grille,

Figure 3 is a vertical section of the grille shown in Figure 1 with provision for supporting a radiator and shield,

Figure 4 is a vertical section showing the grille and radiator and shield in elevation,

Figure 5 is a view in perspective of the grille constructed according to the principles of my invention,

Figure 6 is a vertical section taken along the lines 6—6 of Figure 4, and

Figure 7 is a vertical section of a modified form of the device showing the radiator and shield supported above the grille by the wall of the room.

Referring more particularly to the drawings, 10 designates the wall having a duct 11 below the floor 12 to which fresh air is supplied by means of a blower. The floor is provided with an elongated opening 13 adjacent the wall 10 and below a grille 14 which is constructed in accordance with the principles of my invention.

The grille has a rear wall 14, and a front wall 15 which is inclined towards the rear wall and of less height than said rear wall, the inclination of the front wall restricting the discharge opening 16 so that in effect a nozzle is provided whereby the air forced from the mouth of said grille will not only tend to travel outwardly and upwardly along the diagonal of the room, but will have its velocity increased. End walls 17 connect the front and rear walls, and a flange 18 is provided having perforations which secure the grille to the floor of the room. It will be noted that the flange 18 is formed along the front and end walls. Inclined ribs or bars 19 connect the upper edge of the front wall 15 with the rear wall and at points along the rear wall which are adjacent the upper edge 20 of said wall. In order to facilitate the proper direction of movement of the air, as indicated by the arrows in Figure 1, the upper inner face 21 of the front walls 15 is curved slightly outwardly.

Referring more particularly to Figure 2, the grille is identical in construction with the grille shown in Figure 1 but I have employed the grille in this case to not only support a supply pipe 22 for a heating system, but for enclosing a return pipe 23. The supply pipe is provided with the usual clamping means which are connected with bolts 24. These bolts are adapted to be

threaded into perforations formed in the upper end of the front wall 15 of the grille as will be presently described with reference to the construction shown in Figures 3 and 6. It will be appreciated that the size of the grille shown in Figure 2 may be reduced and the slats or ribs 19 may be dispensed with if desired so that the grille in this case serves a double purpose for concealing the 10 return steam pipe 23 and for carrying and supporting the supply pipe 22, and also for locating the steam pipe at a convenient place along the wall near the floor line of the room, and such grille may be employed 15 for housing and supporting hot steam pipes while also providing a means for supporting a radiator. This form of grille in connection with the supply and return pipes is particularly adapted for use in heating the 20 basement rooms of a building.

Referring more particularly to Figures 3, 4 and 6, a grille 14^a is similar in all respects to the grille shown in Figure 2, since in both cases the upper end of the front wall 25 is 25 enlarged as shown at 26 to provide bosses having internally threaded passages 27 adapted to receive bolts 28, these bolts are adapted to receive by-passages formed in radiator supports 29. These supports run 30 longitudinally of the upper edge of the front wall 25 of the grille for the length of the radiator, and the radiator is secured in any approved manner to the supports 29. In such a case, a grille is secured to the floor 12 35 and heated air is forced between the walls 25 and 30 of the grille to the open end or nozzle 31, past the grille bars or slats 32, then upwardly and through the spaces between the vertical sections 33 of the radiator 40. As the air is forced through the sections of the radiator, the air is caused to whirl and provide for the proper diffusion of the heated air in the room, and dormant air which is associated with or in close 45 contact with the radiator is placed in circulation so that the greatest efficiency is had for the heating system.

In order to force the air upwardly and over the surface of the radiator, it may be 50 advisable in some instances to employ a shield which is connected by U-shaped brackets 35 and 36 to the radiator by means of bolts 37. This shield prevents the heat from being forced directly forwardly from 55 the radiator and thus protects the person sitting near the radiator from the direct contact with the heated air and also the heat of the radiator, since the air is directed upwardly and away from the radiator. The 60 shield generally designated by the numeral 38 has an outside facing 39 formed of sheet steel, while the inside portion is faced as shown at 40 with asbestos mill board or other suitable insulating material. The 65 shield, as shown at 41, is bolted directly to

the outside flange of the brackets 35 and 36.

In the modified form shown in Figure 7, the radiator, instead of being supported upon the front wall 15 of the grille 14, is connected by means of bolts 42 to the wall 10 of the room, and a sleeve 43 on said bolts aids in spacing the radiator 34 from said wall. Brackets 35 and 36 support the shield 38 in spaced relation with said radiator. In this construction the air, as has been stated, is preliminarily heated and is forced through the passage 44 of the grille 14 up through the nozzle 16, then upwardly between the wall and the radiator through the radiator and then baffled by the shield 38 so that the 75 air will be directed upwardly and away from the radiator, as has been described relative to the construction shown in Figure 6.

Since the air is supplied by a blower 85 through the grille and past the radiator on the pipes 22 and 23 the air is heated more rapidly, due to the fact of the higher speed of the air when coming in contact with the surface portions of the radiation.

What I claim is:—

1. A heating device comprising a grille 90 having a rear wall, a front wall inclined towards the rear wall and of less height than the rear wall, end walls connecting the front and rear walls, the upper and lower ends of the grille being open, bars connecting the upper edges of the front wall with the rear wall, and inclined at an angle to the horizontal, a supply pipe carrying a heating medium, means for securing the supply pipe 95 to the upper edge of the front wall, and a return pipe for the heating medium disposed between the front and rear walls of the grille.

2. A heating device comprising a grille 100 having a rear wall, a front wall inclined towards the rear wall and of less height than the rear wall, end walls connecting the front and rear walls, the upper and lower ends of the grille being open, bars connecting the 105 upper edges of the front wall with the rear wall, and inclined at an angle to the horizontal, and a radiator carried by the front wall of the grille.

3. A heating device comprising a grille 110 having a rear wall, a front wall inclined towards the rear wall and of less height than the rear wall, end walls connecting the front and rear walls, the upper and lower ends of the grille being open, bars connecting the 115 upper edges of the front wall with the rear wall and inclined at an angle to the horizontal, a radiator, and means for supporting the radiator in vertical position on the upper edge of the front wall, and in advance of the 120 upper opening in said grille.

4. A heating device having a rear wall, a front wall and end walls, the grille having a restricted discharge opening along its upper edge and an intake port of larger dimen- 125 130

- sions than the discharge port, an air passage connected with the intake port to which is adapted to be supplied air under pressure, a radiator supported above the grille and 5 forwardly of the rear wall of said grille whereby air from the grille will be circulated upwardly and through the radiator for maintaining the air in circulation through the same.
- 10 5. A heating device comprising a grille having a front wall and a rear wall with the front wall of less height than the rear wall, a radiator supported on the front wall of
- the grille, the upper end of the grille being open with the radiator slightly disposed in 15 the plane of said opening.
6. A heating device comprising a grille having a rear wall, a front wall of less height than the rear wall, the upper and lower ends of the grille being open for the 20 passage of air, a radiator supported above the opening in the grille whereby air passing through the grille will pass up through the radiator.

SAMUEL R. LEWIS.
